To all whom it may concern:

Be it known that I, STANLEY A. COHEN, a citizen of the United States, and a resident of the city of New York, borough of Manhattan, in the county and State of New York, have invented and produced a new, original, and ornamental Design for a Game-Chip, of which the following is a full, clear, and exact description.

Reference is to be had to the accompanying drawings, forming a part of this specification, in which—

The invention relates to chips used in games

of cards and the like; and the design consists of the representation of the profile of a human head, an urn, and scrolls, all inclosed in a circular border.
